LOAD SPACING ASSEMBLY

Clarence M. Ellis, Lodi, Calif., assignor of one-third to J. E. Devine and one-third to James M. Prentice, both of Lodi, Calif.

Application November 13, 1945, Serial No. 627,989

6 Claims. (Cl. 105—369)

1

This invention relates to the spacing of rows of stacked boxes of produce in railroad refrigeration cars, and as to all common subject matter this application is a continuation of my application filed October 4, 1943, Serial No. 504,874.

It is an object of the invention to provide a novel and effective spacing means for such rows of stacked boxes of produce in a manner to effectively hold the same against displacement in the car while in transit, and at the same time to provide for a free circulation of air about the rows of stacked boxes in order to minimize the possibility of spoilage of the produce.

It is a further object of the invention to provide such a spacing means which can be quickly arranged in place as the car is loaded with the boxes thereby reducing labor costs.

A still further and important object of the invention is to provide such a spacing arrangement as will permit the use of lengths of ordinary standard dimension lumber as the spacing elements. These can be reclaimed and sold for other uses at the point of unloading the car. In this respect my invention distinguishes from those loading assemblies heretofore used in the art, and which require specially manufactured spacing elements which have no value and are not reclaimable for other uses upon arrival of the car at the point of unloading.

A still further object of the invention is to so provide and locate the spacing elements so that it is not required that nails or the like be driven into the boxes of the load, which latter has been necessary in connection with certain types of load spacers heretofore used.

A further object of the invention is to produce a simple and inexpensive device and yet one which will be exceedingly effective for the purpose for which it is designed.

These objects are accomplished by means of such structure and relative arrangement of parts as will fully appear by a perusal of the following specification and claims.

In the drawings similar characters of reference indicate corresponding parts in the several views.

Figure 1 is a longitudinal vertical section through one-half of a refrigerator car showing my improved box spacing elements in position therein.

Figure 2 is a vertical cross sectional view of the car likewise showing the spacing elements in position between the rows of stacked boxes.

Figure 3 is a sectional view on a line 3—3 of Fig. 1.

Figure 4 is a perspective view of a securing

2

plate for fastening adjacent spacing elements together.

Referring now more particularly to the characters of reference on the drawings, numeral 1 designates generally a refrigerator car having the usual central door entrances 2. At each end of the car is the ice bunker 3 having the usual foraminous bottom 4 opening into a passage way 5. The passage way 5 in turn communicates with a passage way 6 between the solid floor 7 of the car and a false floor 8 spaced from the floor 7. The floor 8 is made up, as usual, of spaced-apart slats, which in some types of cars extend across the car at right angles and in other types of cars extend across the car diagonally. In either event, however, the slats are spaced apart to form intervening air spaces or slots 9 which open from the space 6 into the body of the car.

The numeral 10 designates the rows of stacked boxes of produce. In some instances the boxes are stacked end to end longitudinally of the car, and in other instances they may be stacked end to end transversely of the car, but since the application of my invention thereto would be the same in either event, I have shown in Figs. 1 and 2 the boxes as they appear in end to end relation transversely of the car.

As the rows of boxes are stacked in the car a space 11 is left between the ends of the several rows and the side of the car and spaces 12 are left between the rows of stacked boxes at intermediate points transversely of the car. These spaces may be left directly between each row of stacked boxes and the next row or two rows of boxes may be stacked end to end at each side of the car with one central row in between, and the spaces 12 being left only between the single row and the adjacent ends of the double rows as shown quite clearly in Fig. 2. My improved spacing elements 40 are arranged in the novel manner, which is one of the concepts of my invention, in the spaces 11 and 12.

My invention contemplates the use of spacing elements made up of ordinary lumber pieces of standard dimensions cut into suitable lengths. I prefer to use for my purpose lumber pieces which are oblong in cross section and usually these would be regular 2" x 4" lumber. These lumber pieces are cut into suitable lengths so that the over-all length of such lumber pieces, as used, will be a considerable amount greater than the height of rows of stacked boxes so that when the lumber pieces are disposed vertically adjacent the rows of boxes they will project well above the same, as shown clearly in Fig. 1.

I will now describe the novel method of disposing these lumber pieces in the spaces between the rows of stacked boxes in order to accomplish the objectives of my invention and which arrangement constitutes the essence of my inventive concept.

Starting at the rear end of the car, and as the boxes are stacked, I first dispose a lumber piece 13 so that its lower end is in contact with the false floor 8 adjacent one lower corner of the stack of boxes. The lumber piece is then disposed diagonally across the stack to project above the same at the opposite upper corner of the stack. Another lumber piece is then placed in the reversed order so that it crosses the upper corner of the stack adjacent the upper corner across which the first piece has been disposed making an inverted V so that the lower end of the second piece then comes to rest on the floor 8 adjacent the opposite lower corner of the second stack.

At the apex 14 of the inverted V, formed by these two diagonally extending pieces, the two pieces come in contact with each other, but below such apex there is an open space 15 above the top level of the stacks of boxes 10 so that there may be a free flow of air therethrough.

In order to hold the two pieces together at their apex I provide a small metal plate 16 which has a V-shaped channelled projection 17 adapted to fit partly into the open space 15, the plate then being nailed to each of the lumber pieces by means of nails or other fastening means 18. By means of this plate the two adjacent upper ends of the two lumber pieces are securely fastened together and will not displace relative to each other. At the same time the channel in the plate 16 permits the flow of air through the opening 15 even if the plate 16 is positioned close to the top of the stacks of boxes.

At their lower ends the pieces 13 frictionally engage the floor 8 only and are prevented from any relative sliding movement by engagement with the edges of the slots 9. As the stacks of boxes continue to be piled in the rows, other sets of lumber pieces 13 are progressively added in the same manner and form as above described so that the final pattern of the spacing elements between the rows of stacked boxes is of zig-zag form as shown quite clearly in Fig. 1. Adjacent lower ends of the members of the pattern are spaced apart somewhat as at 19 in order to allow of some leakage of air from the passage way 6 therebetween.

The same zig-zag of the arrangement of the spacing elements is followed at each point where the boxes are spaced apart and also at the space between the outside rows of stacked boxes and the side walls 20 of the car.

While most boxes in which produce is shipped are of a standard size, it sometimes happens that there will be a slight variance in such size. Also while most refrigerator cars are of a standard width, there are instances in which there is a variance in such width. Since my lumber pieces are preferably of oblong shape in cross section this affords me an opportunity to place them in different relative positions as to cross section in order to compensate for such slight variations under the conditions noted. By using standard 2" x 4" lumber pieces or pieces of like standard dimensions, I may so position these in the different spaces as may compensate for the variance therein. This variance is usually not great and by having a differential of from 2" to

4" to reckon with, I find that pieces of this standard size can be so placed as to practically take care of all such variations. However, irrespective of the exact position of the pieces relative to their cross sectional dimensions, the basic arrangement of the zig-zag pattern is adhered to and the same fastening means is used.

As shown by the arrows in Fig. 1, it will be obvious that when the lumber pieces are in this zig-zag pattern, arranged in the manner described, refrigerated air, passing from the bunker 3 into the passage way 5 and hence to passage way 6, may pass through the slots 9 into the spaces formed by the inverted V of the lumber pieces and thence upwardly along the sides of the boxes and out through the openings 15 so that there is a continuous circulation of the refrigerated air about the sides of the boxes in the spaces 11 and 12.

It will also be apparent that the lumber pieces, positioned as described, effectively hold the boxes properly spaced apart and against endwise deflection.

Both of the above results are attained through the use of the very inexpensive and ever-ready lumber pieces of standard dimensions which are usually purchasable at any point at which the car is being loaded; which can be handled without any pre-manufacturing problems and which have many general uses to which such lumber pieces can be put when the loaded car arrives at its point of unloading. Also by bracing the zig-zag pattern against the bottom of the car and then securing the converging upper ends together with the plate 16 there is no opportunity of the spacing elements becoming displaced in transit and it is, therefore, unnecessary to nail or otherwise fasten them to the box ends.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful and upon which Letters Patent is desired:

1. A spacing assembly for spaced parallel rows of stacks of boxes disposed in a car, such assembly comprising a plurality of upstanding pieces of lumber disposed in the spaces between the adjacent rows of boxes, each piece of lumber extending diagonally across one stack of boxes from a point adjacent one lower corner thereof to a point adjacent the opposite upper corner thereof, the pieces across adjacent stacks extending in relatively opposite directions so that the upper and lower ends of the pieces on adjacent stacks respectively converge toward each other, whereby to form a zig-zag pattern in the space along the row of stacks, and means to maintain said pieces in such position.

2. An assembly as in claim 1 in which at least one set of the converging ends of the pieces are secured together.

3. An assembly as in claim 1 in which the lumber pieces are oblong in cross section whereby they may be selectively positioned with their wide sides or their narrow sides engaging the boxes.

4. An assembly as in claim 1 in which the upper converging ends of the lumber pieces extend above the stacked boxes a distance sufficient to form air spaces between such converging ends at a point above the stacks of boxes.

5. An assembly as in claim 1 in which the upper converging ends of the lumber pieces extend above the stacked boxes a distance sufficient to form air spaces between such converging ends and metal plates secured across each pair of such converging ends to secure them together. 10

6. An assembly as in claim 1 in which the upper converging ends of the lumber pieces extend above the stacked boxes a distance sufficient to form air spaces between such converging ends and metal plates secured across each pair of such converging ends to secure them together, said plates having channel shaped projections fitting into such air spaces.

CLARENCE M. ELLIS.
